UNITED STATES PATENT OFFICE.

MENLO E. MOORE, OF CHICAGO, ILLINOIS.

DESIGN FOR A THEATRICAL APPLIANCE.

44,317.

Specification for Design.

Patented July 8, 1913.

Application filed April 23, 1913. Serial No. 763,170. Term of patent 3½ years.

To all whom it may concern:

Be it known that I, MENLO E. MOORE, a citizen of the United States, and a resident of the city of Chicago, in the county of Cook and State of Illinois, have invented a new, original, and ornamental Design for Theatrical Appliances; and I do hereby declare that the following is a specification thereof, reference being had to the accompanying drawing, forming a part hereof, in which the figure is a perspective view of a theatrical appliance, showing my new design.

I claim:—

The ornamental design of a theatrical appliance as shown.

In testimony whereof I have hereunto set my hand in the presence of two subscribing witnesses.

MENLO E. MOORE.

In the presence of—

GEO. ROB QUIN, Jr.,
THOMAS L. MILBURN.
